ELECTRICAL REPEATER TUBE

Alexander McLean Nicolson, New York, N. Y., assignor to Communication Patents, Inc., New York, N. Y., a corporation of Delaware

Application March 22, 1932, Serial No. 600,438

9 Claims. (Cl. 250—27.5)

This invention relates to repeater devices such as electrical discharge tubes for rectifying or amplifying electrical currents and voltages. Devices of this type are thermionic discharge tubes producing electron emission from a heated element, and glow discharge tubes producing ionization of a gas between cold electrodes. The present invention is related to the latter type.

The object of the invention is to efficiently repeat electrical signals with fidelity.

Another object of the invention is to rectify and amplify electrical currents in a discharge device having no thermionically active element.

A further object of the invention is to control the ionization produced by a piezoelectric crystal in vibration and to employ such a device as a detector or amplifier of electrical signals.

Vacuum tube amplifiers of many types are well known such as those commonly used in radio communications in which a thermionically active element and a plurality of cold electrodes are positioned in an evacuated envelope. It is also known in the art how a similar repeater tube may be constructed utilizing solely cold electrodes, and in which the gas is ionized by a potential difference between two electrodes. Such discharge tubes have been used as radio and audiofrequency amplifiers and detectors of radio signals.

One other feature of the present invention is familiar to those skilled in the art and that is, the production of ionization by a vibrating piezoelectric crystal element in a partial vacuum. The regions of ionization form various patterns around and about the crystal depending upon the manner in which the crystal is cut, and the positioning of the electrodes thereon. Such crystals have been used as frequency indicators and for other like purposes but in the present invention the glow produced by the crystal is controlled by an anode and control electrode or a combination thereof, so that the combination functions as a repeater tube similar in operation to those mentioned above.

The invention in brief contemplates placing a piezoelectric crystal in an envelope evacuated to a pressure of several millimeters of mercury, the envelope containing either neon, helium, nitrogen, or a mixture thereof. The electrodes are placed on the crystals in suitable positions to produce the greatest amount of ionization.

A positive anode is placed near the crystal but separated by a control electrode to control the flow of negative ions to the positive electrode.

The invention will be more fully understood by

reference to the following description taken in conjunction with the drawing in which:

Figs. 1, 2 and 3, show different modifications of repeater tubes employing the principles of the invention;

Figs. 4, 5, 6, 7, 8, 9, and 10 show detailed mountings of crystals which serve as ionization sources for tubes and which may be employed in the systems of Figs. 1, 2 and 3; and,

Fig. 11 shows an embodiment of the invention with the energizing electrodes outside the tube.

Referring specifically to Fig. 1, a glass envelope 5 having a press 7 is mounted upon a base 6. In the press 7 are four seal-in conductors, two of which connect to two electrodes 9 and 10 for a crystal 12, the conductors being sufficiently rigid to support the crystal in the position shown. An anode element 13 is shown in the form of a flat plate but may be a cylinder surrounding the crystal 12 and its electrodes. The third element 75 in the envelope 5 is a control electrode 14 which is positioned between the crystal 12 and anode 13 and which may be in the form of a mesh plate or meshed cylinder surrounding the crystal. These elements are mounted in the usual manner well known in the art of thermionic tube construction.

The respective connections of the electrodes above mentioned to certain external elements are shown for purposes of explaining their function. Electrodes 9 and 10 are connected across a source 85 of alternating current 16 which is shunted by a potentiometer resistance 17. The source 16 supplies to the crystal 12 a voltage having a frequency of approximately that of the crystal, the frequency of the source being adjustable by means of a variable condenser 18, although it is to be understood that the crystal will produce ionization at other frequencies. The anode 13 is connected through an output inductance 20, which may represent any form of output circuit commonly known in the art, to a variable contact 21 on the resistance 17. To this same contact, the control electrode 14 is connected through an input inductance 23. The anode and control electrode polarizing batteries are shown as 24 and 25, respectively.

This tube operates in substantially the same manner as the ordinary tube and could be used in any receiver having tubes with cathodes supplied from an alternating source. The negative ions and electrons produced by ionization of the gas by crystal vibration are attracted to the anode 13, this attraction being controlled by the static and dynamic polarizing of the control electrode 14.

The mounting shown in Fig. 1 is of one particu-

lar type such type being a crystal of cylindrical shape having thereon an even number of alternatively connected electrodes. In this manner potentials are distributed at the pole faces producing an efficient ionization element.

Now referring to Fig. 2, a second method of mounting the crystal is illustrated. An envelope 27 has a press 28 supporting electrodes 29 and 30 which in turn support a square or rectangular shaped crystal element 31. The electrodes 29 and 30 may be cup-shaped so as to hold the crystal therein loosely, the vibration thereof producing a glow between the electrodes on the face of the crystal. In the envelope 27 are also an anode 33 and a control electrode 34 mounted on the press 28 in the same manner as that shown in Fig. 1. The four conductors from this tube may connect in the circuit shown in Fig. 1 in similar manner or may be connected in any equivalent circuit.

20 In Fig. 3 a tube envelope 36 has positioned therein only two elements, one being a crystal 37 with its two electrodes 38 and 39, and the other an anode element 40 which may be U shaped or hemispherical. The crystal 37 is held in position by its electrodes 38 and 39 or it may be supported independently from the press in any well known manner. Such a tube is especially operative as a rectifier for transforming alternating current or direct current or as a detector of modulated signals.

Referring now to the cathode construction and mountings in Fig. 4, a three electrode, two-section crystal unit is illustrated, having two portions 43 and 44 and three electrodes 45, 46 and 47. Electrodes 45 and 47 are connected to the terminals of the secondary of a transformer 49 while the electrode 46 is connected at the mid-tap thereof. This construction permits exposing large surfaces of the crystal to the gas to produce ionization. The transformer 49 may be supplied from an alternating current source 50.

In Fig. 5 two crystal sections 52 and 53 shown by the different directions of cross hatching are held together by means of a pin 54 of metal, glass or lavite. Thin metal electrodes 55 and 56 are inserted between the sections during their assembly, the electrodes applying to the crystals the potentials necessary to produce ionization. The electrodes used in any of the constructions of this invention may be comprised of aluminium, copper or platinum with satisfactory results. The electrodes 55 and 56 are supplied from the alternator 57.

It has been found in the production of ionization by crystal oscillations that it is advisable in some cases to have the electrodes positioned away from the crystal to allow the crystal more freedom of vibration, this distance being approximately one millimeter. In Fig. 6, such a construction is illustrated wherein a crystal 60 is shown encircled by bands 61 of insulating material such as glass or lavite, upon which are placed perforated electrodes 62 and 63, the perforations being advisable to permit the ions to more readily circulate about the crystal. The crystal may be cylindrical, rectangular, or square. The electrodes may be polarized from a source of alternating potential 65.

In Fig. 7 another construction showing electrodes positioned away from the crystal is illustrated in which a crystal 67 has an insulating bead 68 placed in a hole through the crystal and upon which is fastened electrodes 69 and 70 which are polarized from source 71.

75 In Fig. 8 a construction is shown similar to that

of Fig. 5. In this embodiment, a crystal has two sections 72 and 73 shown by the different directions of cross hatching bolted or cemented together with an electrode 74 therebetween, and a second electrode 75 attached to one of the external faces of a section, the electrodes being supplied from a source 76. This construction provides a large open face for ionization and is particularly efficient.

80 In Fig. 9, flat crystal plates 80 and 81 are mounted on supports 82 and 83 of insulating material such as glass or lavite. Electrodes 85 and 86 for the plates are mounted similar to those in Fig. 8 but do not touch the crystals since they are fastened to the supports 82 and 83. This construction provides absolute freedom of vibration for crystal 80, the vibration of crystal 81 being transmitted to crystal 80 through the end supports. This structure may be polarized from a source 87.

85 In Fig. 10 a cylindrical piezoelectric crystal 90 has an electrode 91 placed around it as a cylinder, and an electrode 92 placed at one end thereof, as a flat plate, these electrodes being polarized from a source 93. Ionization in such a crystal construction will be produced at the free end of the 100 crystal in the well known manner.

90 The modification in Fig. 11 varies from the constructions in Figs. 1, 2 and 3, by employing an envelope 95 in which a recess has been formed to accommodate a crystal cathode 96. The crystal 105 is energized from electrodes 97 and 98 mounted on the outside surface of the recess or adjacent thereto, this connection leaving an unobstructed ionization surface for the crystal. A control electrode 99, anode 100, and an anode return electrode 101, constitute the other elements within the tube. The electrode 101 may be against the crystal or only within the ionized region to complete the output circuit for this arrangement.

95 Although several types of crystal mountings for 110 use as cathodes have been shown, it is to be understood that there are other mountings and supports for crystals which will produce ionization but that any such equivalent constructions, when used with anodes and control electrodes as disclosed above, are deemed to be within the scope of the appended claims.

100 What is claimed is:

1. An electrical repeating device comprising a pair of electrodes adapted to be connected to an alternating voltage source, enclosing means for said electrodes, a gas in said enclosing means, an ionization element positioned between said electrodes to ionize said gas when said alternating current source is connected thereto, an anode electrode and a separate control electrode positioned between said ionization element and said anode to control the flow of current from said element to said anode in accordance with the voltage on said control electrode.

105 2. An electrical repeating device comprising a partially evacuated envelope, a pair of electrodes located in said envelope adapted to be connected to an alternating current source, a gas in said envelope, a piezoelectric crystal element positioned between said electrodes for ionizing said gas when said electrodes are connected to said alternating current source, an anode electrode, and a separate control electrode positioned between said ionization element and said anode.

110 3. An electrical detecting device comprising a partially evacuated envelope, a gas in said envelope, a piezoelectric crystal element for ionizing said gas, electrodes for said crystal element, means for connecting said electrodes to an alter- 115

- nating voltage supply, an anode electrode positioned in proximity to said crystal, and a separate control electrode positioned between said crystal electrodes and said anode electrode.
- 5 4. An electrical amplifying device comprising a partially evacuated envelope, a piezoelectric crystal element, electrodes for said element adapted to be connected to an alternating voltage supply, an anode element located within said envelope, and a separate fourth electrode within said envelope positioned intermediate said crystal electrodes and said anode element for controlling the discharge of current from said crystal element to said anode.
- 10 5. An electrical repeating device comprising a partially evacuated envelope containing an ionizable gas, a pair of electrodes located in said envelope, means intermediate said electrodes for producing ionization of said gas an anode, and means within said envelope independent of said pair of electrodes and said anode for controlling the flow of ions in said gas after their production.
- 15 6. An electrical repeating device comprising a partially evacuated envelope containing an ionizable gas, a pair of electrodes located within said envelope, a piezoelectric crystal element positioned between said electrodes for producing ionization of said gas when polarized, an anode and means within said envelope independent of said pair of electrodes and said anode for controlling the flow of ions produced in said gas.
- 20 7. An ionization element for use in a partially evacuated envelope having an insulated electrode therein, comprising a plurality of cold electrodes, and a plurality of piezoelectric crystal elements alternately mounted with respect to said electrodes.
- 25 8. An ionization element for use in a partially evacuated envelope having insulated electrodes therein, comprising a pair of electrodes, said electrodes having mounted thereon a plurality of piezoelectric crystal elements, and means fastening said elements together around said electrodes.
- 30 9. An ionization element for use in a partially evacuated envelope having an ionizable gas, comprising a pair of piezoelectric elements, a pair of insulating supports for said elements, an electrode positioned between said piezoelectric elements and out of contact therewith, and a second electrode positioned near one face of one of said elements, the vibration of said piezoelectric element between said electrodes being transmitted from said piezoelectric element to said other piezoelectric element through said supports.
